UNITED STATES PATENT OFFICE.

FRANKLIN TINSMAN, OF PHILLIPSBURG, NEW JERSEY.

BOX INSERT.

Application filed April 26, 1924. Serial No. 709,258.

To all whom it may concern:

Be it known that I, FRANKLIN TINSMAN, a citizen of the United States, and resident of Phillipsburg, in the county of Warren 5 and State of New Jersey, have invented certain new and useful Improvements in Box Inserts, of which the following is a specification.

My invention relates to box inserts commonly known as "frogs."

Devices of this type are most generally used to alter the interior formation of rectangular boxes for the purpose of rendering them suitable to receive hosiery when the 15 latter are folded in the usual manner for display and sale.

Frogs of this character are constructed from card board blanks designed in such a way as to be foldable to impart the desired 20 interior formation when inserted in a box. Owing to the peculiar interior formation required it has been impossible heretofore to construct such frogs without exposing to view, when folded and inserted, both faces 25 of the blank with the result that the economy of constructing such devices from card board finished on one side only has not been available. It is therefore, the purpose of 30 my present invention to so design the blank or blanks that when the frog is folded and inserted in its related box only one face of such blank will be exposed to view, thereby enabling the use of cardboard coated or finished on one side only with the obvious resulting economy of manufacture.

Furthermore, it is the purpose of my present invention to so design the blank or blanks from which the frog is folded that the same can be initially scored and folded 40 by a die press with corresponding saving in labor necessary to develop the manufacture of the frog to a status where it is ready for insertion in the desired box.

It is also the purpose of my invention to 45 so construct the blank or blanks that the necessity of hand folding and locking operations between the parts to maintain the frog folded are entirely eliminated, thereby simplifying the insertion of the frog in a desired box.

I will describe my invention in the best forms known to me at present, but it will be obvious that the same is susceptible to 55 changes in forms and proportions and to desirable additions with the exercise of only

ordinary mechanical skill and without departing from the scope thereof as set forth in the appended claims.

In the drawings chosen to illustrate my invention—

Figure 1 is a plan view of my invention showing the same in position in a box;

Figure 2, a longitudinal section of Figure 1;

Figure 3, a section on the line 3—3 of Figure 1;

Figure 4, a section on the line 4—4 of Figure 1;

Figure 5, a plan view of the blanks from which the elements of my improved frog are 70 folded; and

Figure 6, a detail perspective view of elements of my improved frog embodying a slightly modified construction.

In constructing my improved frog I utilize 75 separate blanks A and B (Figure 5) formed preferably of card board, the blank A being utilized in producing the bottom, side platforms, side walls and an end wall of the frog and the blank B to produce the end 80 platform all as will hereinafter appear.

As will be obvious, the blank A is of substantially T-shape in outline and is provided with longitudinal scores 10—11 and 12—13 with the former disposed a greater 85 distance apart than the latter. The ends of the scores 10—11 adjacent the scores 12—13 are converged as at 14—15. These scores 10—11—12—13—14—15 serve to define the bottom of my improved frog when the latter is folded, as will hereinafter appear. Outwardly of the score 13 the blank is provided with longitudinal scores 16 and 17 which are connected at their inner ends by a score 18 parallel to the score 15. Likewise, 90 outwardly of the score 12 the blank is provided with longitudinal scores 19 and 20 which have their inner ends connected by a score 21 parallel to the score 14. The outer ends of the scores 12—13 are connected by a 95 transverse score 22 and at either end of this score the blank is slitted transversely as at 23 and 24 to provide an end flap 25 for the frog. Between the inner ends of the scores 12 and 19 I provide the blank with an opening 26 while a corresponding opening 27 is provided between the scores 13 and 16. A slit 28 connects the inner ends of the scores 12 and 13 on a line with corresponding walls of the openings 26 110

and 27 and thereby separate the bottom of the frog into sections 28' and 29 for a functional purpose that will presently appear. Slits 30 and 31 parallel respectively to the adjacent walls of the openings 26 and 27 are formed in the blank and said slits in conjunction with edges of the blank and scores 10 and 11 define side elements 32 and 33 of the frog, said elements being adapted 10 to be folded upwardly on scores 10 and 11 respectively as shown in Figure 4.

Referring now to the side platforms of the frog, indicated generally in Figure 1 at C and D respectively, it will be apparent 15 that by folding the blank upwardly on the scores 12 and 14, then outwardly on scores 19 and 21, and then downwardly on the score 20, the platform C will be formed as embodying an outer side 34 having a free 20 end, a top 35, and an inner side having a section 36 parallel to the side 34 and a section 37 inclined outwardly toward the side 34. Likewise, by folding the blank upwardly on scores 13 and 15, then outwardly 25 on scores 16 and 18, and downwardly on score 17, the platform D will be formed as embodying an outer side 38 having a free end, a top 39, and an inner side having a section 40 parallel to the side 38 and a section 41 inclined outwardly toward the side 38. When the platforms C and D are thus 30 formed by folding the blank as specified, the flap 25 is folded on the score 22 against the adjacent ends of said platforms. While I 35 have described the steps for manually effecting the folding of blank A, it will be understood that in actual commercial production such blank, owing to its design and arrangement of scores, will be initially folded by a 40 suitable die press and after this is accomplished a mere gentle inward pressure on the sides will impart the necessary shape thereto to form the frog and enable same to be easily forced into the desired box, such box 45 being indicated at E in Figures 1 to 4. It will also be observed that when the blank A is folded and inserted in the box E as described only one face of the material from 50 which the blank is formed is exposed to view when such box is opened, thus enabling me to attain the advantage of utilizing card board coated on only one side in the manufacture of the frog.

When the blank A is collapsed as shown 55 in Figure 5 the adjacent edges of the inner side sections 36 and 37 are disposed at an angle, as also are the adjacent edges of the inner side sections 40 and 41. Further, the side edges of the sections 36 and 40 are perpendicular to the scores 12-19 and 13-16 60 respectively, while the side edges of the sections 37 and 41 are perpendicular to the inclined scores 14-21 and 15-18. Now with these conditions existing in conjunction with 65 the recesses 26 and 27 and the slit 28, it will

be obvious that as the blank is folded or set up the section 29 of the bottom will move toward the section 28' and overlap the latter (as shown in Figure 1) and at the same time the adjacent edges of the inner side sections 70 of respective platforms C and D will be automatically brought into substantially abutting relation, thus disposing opposed sides of said platforms, so that outer portions of said sides will lie parallel to each other, 75 while their inner portions diverge in a direction away from the section 28' of the bottom. It will be further noted that as the section 37 and element 32 hinge or pivot on different axes the inner end of the element 32 will engage between the section 37 and outer side 34 of the platform C when the latter is folded or set up as shown in dotted lines in Figure 1. Under the same 80 conditions and for the same general reasons 85 the inner end of the element 33 will engage between the section 41 and outer side 38 of the platform D as shown in dotted lines in Figures 1 and 2.

My improved frog further embodies an 90 end platform formed from the blank B shown in Figure 5, the folder or set up platform being illustrated in Figures 1, 95 2 and 4. In forming the end platform of the frog from the blank B I provide the latter with triangularly arranged scores 42, 43 and 44 which define the top 45 of the platform. I further provide the blank B with scores 46 and 47 parallel respectively to the scores 42 and 43 and it will be observed in this connection that owing to the 100 shape of the blank B the scores 46 and 47 provide tabs or flaps 48 and 49 for a purpose that will presently appear. I also provide the blank B with scores 50 and 51 extending from the junction of the scores 42 and 43 to the adjacent ends of the scores 46 and 47 respectively. From the foregoing it will be 105 apparent that the defining edges of the blank B and the score 44, when the blank is folded downwardly on the said score, determine one side 52 of the platform and in this instance said side is adapted to lie against one end of the box when the platform is inserted. It will also be apparent that the defining edge of the blank and scores 42, 46 and 50 determine another side 53 of the platform, while the scores 43, 51 and 47 together with the defining edge of the blank determine the third side 54 of the platform. The portion of the blank between the scores 50 and 51 I score centrally as at 55 and when the blank is set up this portion of the blank is folded inwardly on the scores 50, 51 and 55, while the flaps 48 and 49 are folded outwardly on the scores 46 and 47 respectively. From the foregoing it will be obvious that the folding of the blank B as specified will produce a triangular platform and when 110 such platform is inserted in the box E as 115 120 125 130 135

shown in Figure 1 the side 52 of the platform lies against one end of the box, while the sides 53 and 54 engage respective edges of an angular recess 56 formed in the outer 5 end of the section 29 of the bottom of the frog; the flaps or tabs 48 and 49 engaging under said section 29 as clearly shown in Figure 1. By folding the blank between the sides 53 and 54 in the manner shown 10 and described I materially strengthen the structure of the platform and in addition this portion of the blank when so folded possesses an inherent spring action which serves to expand the sides 53 and 54 against 15 the edges of the recess 56 with a resulting spring reaction tending also to force the platform firmly against the adjacent end of box E. These conditions as will be obvious, firmly hold the end platform in place. 20 It will also be noted that the construction and design of blank B has the same advantage as blank A in respect to die folding and the use of card board finished on one side only.

25 In Figure 6 I show a slightly modified arrangement for associating the end platform with the other section of the frog. In this construction the recess in the outer end of section 29 is eliminated and in lieu thereof 30 said section is provided with a triangular opening 57 spaced slightly inward from the outer end of the section; and the end platform is provided with slightly different tabs 58 and 59 on the lower ends of sides 53 and 35 54 respectively, said tabs being engageable beneath the section 29 through the opening 57 as will be obvious.

I claim:

1. A removable frog for boxes comprising a blank foldable to provide a bottom and corresponding oppositely disposed platforms having portions of their inner sides parallel and the other portions of said sides at an angle to the first portions respectively, said 40 angular portions having direct hinge connection with the bottom.
2. A removable frog for boxes comprising a blank foldable to provide a bottom and corresponding oppositely disposed platforms having portions of their inner sides parallel and the other portions of said sides at an angle to the first portions respectively, said 45 angular portions having direct hinge connection at their lower ends with the bottom and at their upper ends with the tops of the platforms respectively.
3. A removable frog for boxes comprising a blank foldable to provide a bottom and corresponding oppositely disposed platforms 50 having portions of their inner sides parallel and the other portions of said sides at an angle to the first portions respectively, said 55
- 60

angular portions having direct hinge connection with the bottom and said blank being slotted and recessed between the upper edges of the inner sides of the platforms to divide the bottom into sections and to dispose the adjacent ends of said portions of each platform side at substantially right angles to their respective lines of fold, 65 whereby said ends will move toward each other when the blank is folded and away from each other when the blank is collapsed. 70

4. A removable frog for boxes comprising a blank foldable to provide a bottom and corresponding oppositely disposed platforms extending longitudinally of the bottom and including inner and outer sides and a top, and lateral flaps on the bottom engaged, when the frog is folded, between the 80 sides of its related platform.

5. A removable frog for boxes comprising a blank foldable to provide a bottom and corresponding oppositely disposed platforms, each of said platforms extending 85 longitudinally of the bottom and comprising inner and outer sides and a top, said inner side being formed of a portion parallel to the longitudinal axis of the bottom and a portion inclined to said axis, and lateral flaps 90 on the bottom extending from the platforms toward the other end of said bottom, the inner edges of said flaps being inclined toward the platforms, whereby the inner ends of each flap, when the frog is folded, will 95 engage between the inclined portion of the inner side and the outer side of its related platform.

6. The combination with a rectangular box; of a removable frog therein composed 100 of separate sections each foldable from a blank, one of said sections forming the bottom and side platforms of the frog and the other an end platform, said last named platform having extending flaps at its lower end 105 engaging beneath the bottom of the other section.

7. An end platform section for removable box frogs formed from a blank having triangularly arranged lines of fold defining the 110 top of the platform, flaps at each side of the top for forming the sides of the platform, one of said flaps being free at its sides and the others connected at their adjacent sides, said connection having a central line of fold 115 whereby it is foldable inwardly centrally, when the platform is set up, to bring the adjacent sides of the flaps connected thereby into abutting relation, and tabs on the free ends of the last named flaps.

In testimony whereof I hereunto affix my signature.

FRANKLIN TINSMAN.
